UNITED STATES PATENT OFFICE.

WALTER PINELL, OF BERLIN-SIEMENSSTADT, GERMANY, ASSIGNOR TO SIEMENS & HALSKE AKTIENGESELLSCHAFT, OF SIEMENSSTADT, NEAR BERLIN, GERMANY.

TELEPHONE SYSTEM.

Application filed April 5, 1922. Serial No. 549,957.

To all whom it may concern:

Be it known that I, WALTER PINELL, a German citizen, and a resident of Berlin-Siemensstadt, Halske Steg. 4, Germany, have invented certain new and useful Improvements in Telephone Systems, of which the following is a specification.

The present invention relates to circuit arrangement for automatic or semi-automatic telephone systems in which connections can be set up over several exchanges, and in which the impulse transmitting devices can be centralized in one or more exchanges.

In large telephone systems comprising several exchanges it is desirable to centralized the subscribers lines as much as possible, while at the same time it is desirable to economize trunk lines. For this purpose circuit arrangements have already been proposed whereby a connection is set up between two subscribers of a local exchange by first setting numerical switches in another exchange and then effecting a switching operation, by which these numerical switches are released and the speaking connection is set up only over switches in the local exchange.

The invention therefore concerns automatic or semi-automatic telephone systems, in which numerical impulse sending or impulse storing and translating devices are provided at the exchanges. A feature of the invention consists of the provision of switching devices so arranged that, when a subscriber makes a local call, the first numerical switches at another exchange, that have been set by the impulse sender, are released after numerical switches in the local exchange have been connected up; while the release of the trunk line between the exchange of the calling subscriber and the exchange containing the sender is effected only after all the registers have been set.

Several methods of carrying out the invention are shown in the drawings:

Figure 1 diagrammatically shows a telephone area.

Figure 2 and 2^a show the circuit of a semi-automatic system.

Figure 3 shows diagrammatically an arrangement for an automatic telephone system, using selectors, each of which have twenty different groups of bank contacts.

Figures 4 and 4^a represent the circuit of an automatic telephone installation wherein after all the numerical switches at the local exchange have been set, the calling line is switched over from the trunk line to the numerical switches at the local exchange. In the example shown in Figure 5 the switching over of the calling line takes place immediately after a numerical switch has been set.

In Figure 1 a telephone area with four large exchanges is shown. These exchanges A, B, C and D contain all the selectors necessary for establishing a connection namely first, second and third group selectors and final selectors. Furthermore they contain the pre-selecting devices of the subscribers directly connected to these exchanges, and, in the case of semi-automatic systems, the service selectors used for connecting up the operator's position, as well as the impulse sender coupled to the operator's position, whereas in automatic systems the impulse translators take the place of the operator's position. With these large exchanges A, B, C, D are associated several small exchanges (satellites) AU, BU, CU containing only a few of the switches required for setting up a connection. The small exchange AU₁ is directly connected by trunk lines VL₁ to the exchange A. The small exchanges BU₁, BU_{II}, BU_{III} are directly connected to the exchange B by other trunk lines. The other sub-exchanges are similarly connected to their respective main exchanges.

The switches in the exchanges AU₁, A and B are shown diagrammatically. It will be assumed that the subscriber 35348 belonging to the satellite AU₁ wishes to speak to the subscriber 23619 of the exchange B. When he originates the call, the non-numerical switches I VW, II VW connect him to a trunk line VL₁ extending from AU₁ to A. This line is at the exchange A (in a semi-automatic system), connected by a service selector DW with an operator's position. The operator answers the call and sets the first group selector IGW, which has been connected up by the secondary selector ZW, on a connecting line VL₂ leading to the exchange B. The second and third group selectors II GW, III GW, as well as the

final selector LW at the exchange B are then set and the subscribers 35348 and 23619 can converse.

If, however, the subscriber 35348 wishes to be connected with the subscriber 35637 who is connected to the same exchange a switching operation takes place in the exchange A, after the transmission of impulses for setting the first and second group selectors I GW, II GW, whereby a third group selector III GW is connected up at the exchange AU₁. It is operated over the trunk line VL₁ and the auxiliary switch MLW. The final selector is also operated over the trunk line VL₁. The first and second group selectors I GW and II GW in the exchange A are available for other calls as soon as the third group selector III GW has been connected up, but the trunk line VL₁ remains connected until all the trains of impulses have been transmitted.

When all the selectors have been operated conversation between the subscribers 35348 and 35637 takes place over the first and second pre-selectors I VW, II VW, the trunk line VL₃, third group selector III GW and the final selector LW.

The switching operations will now be considered in detail with reference to Figures 2 and 2^a. When the subscriber 35348 calls, the relay R is energized and at its contact 1, closes the following circuit for the rotary magnet D: battery, contacts 1, d, rotary magnet D, contact 4, earth. The first pre-selector I VW seeks a free second pre-selector II VW and when it has found it, the following test circuit is completed: Earth, contact 2, windings I and II of relay T, test wiper c of the first pre-selector I VW, contact 3, relay R₁, battery. Relay T at contact 4 opens the circuit of the rotary magnet D and short circuits at contact 5 its high resistance winding I, whereby the second pre-selector II VW taken into use is marked engaged. Furthermore at contacts 6 and 7 it disconnects the calling relay and at 8 and 9 cuts through the operating leads. Relay R₁ at the second pre-selector II VW is operated. It closes at contact 10 the circuit of the rotary magnet D₁ and prepares at 11 the circuit for the test relay T₁. If the second pre-selector II VW finds a free trunk line VL₁, leading to the exchange A, the following test circuit is closed: Earth, contact 11, windings I and II of relay T₁, contact 12, test wiper c, test conductor of the second pre-selector II VW of the trunk line VL₁, relay C, resistance 13, contact 14, off normal contact 15, battery. Relay T₁ at contact 16 opens the circuit of the rotary magnet D₁, at contact 3 disconnects relay R₁ and at contact 17 switches through the test lead from the first pre-selector I.VW to the trunk line VL₁, so that its high resistance winding I is deenergized. At contacts

18 and 19 the speaking leads a, b are switched through. The bridged relay A responds at the connecting line VL₁, cutting in at contact 20 the circuit for the slow acting release relay V. Relay C is locked over contacts 21 and 22. At contact 23 a circuit is closed over resistances 24 and 25 for the relays C₁ and C₂ connected to the c₁ lead in exchange A. Of the two relays connected in series only relay C₁ can operate. It closes its contacts 26, 27, 28, 29 and 30. The closing of contact 26 connects up rotary magnet D₂ of the service selector DW which is energized as follows: Earth, contacts 31, 26, 32, rotary magnet D₂, contact 33, battery. If the service selector DW finds a free operator's position, the test relay T₂ is energized as follows: Earth, contacts 34, 27, windings I and II of the test relay T₂, wiper 35 of the service selector DW, resistance 36, contact i₄, battery. Relay T₂ responds and at contact 32 opens the circuit of the rotary magnet D₂, at contact 37 it short circuits its high resistance winding I, at contact 38 it prepares the circuit for relay E which is to operate later on, and at contacts 39 and 40 connects the calling line to the operator's instrument.

The secondary selector ZW is operated at the same time as the service selector DW, and its rotary magnet D₃ is energized as follows: Earth, contacts 29, 41, 42, rotary magnet D₃, contact 43, battery. If the secondary selector ZW finds a free first group selector I.GW the following circuit is completed: Earth, contacts 44, 30, windings I and II of relay P, test wiper of the secondary selector ZW, relay C₃, off normal contact 46, battery.

If the calling subscriber requires connection with a subscriber belonging to his own exchange, the operator presses on the keys corresponding to the required number and sends out impulses. The operator's instrument is disconnected at contacts 47 and 48, and at contact 49 the impulse contact 50 is connected to the a lead. Since the impulse contact 50 is closed, the relays A₁ and A₃ are energized. Relay A₁ at contact 51 connects up relay V₁ and relay A₃ at contact 52 connects up the relay V₁.

The operation of the first and second group selectors I.GW, II.GW in the exchange A will now be described, and then an explanation will be given of the effect produced by the trains of impulses on the devices in the exchange of the calling subscriber.

Relay V₁ in the first group selector I.GW completes at contact 652 a locking circuit for relay C₃, which was prepared at contact 53. When impulses are transmitted for raising the first group selector I.GW to the required level, the lifting magnet H is energized as follows: Earth, contacts 54, 55, relay V₂, lifting magnet H, shaft con-

tact 56, battery. During the impulse transmission the relay V_2 remains energized because its armature is slow to release. When the relay A_3 remains energized at the termination of the train of impulses, relay V_2 is deenergized and closes the following circuit for the rotary magnet D_4 : Earth, contact 57, 58, rotary magnet D_4 , contact 59, off normal contact 60 (closed at the first lifting step of the selector) battery. The first group selector I GW hunts for a free second group selector II GW; on finding it, the relay P_1 at the first group selector I GW and the relay C at the second selector II GW are energized as follows: Earth, contact 61, windings I and II of relay P_1 , test wiper of the first group selector I GW, relay C_4 , off normal contact 62, battery. Relay P_1 opens at contact 58 the circuit for the rotary magnet D_4 , short circuits at contact 63 its high resistance winding I, thereby marking engaged the seized second group selector II GW. The impulse relay A_3 is disconnected at contact 64, the speaking leads a, b are switched through at contacts 65 and 66 and at contact 67 the locking circuit for relay C_3 is maintained which would otherwise be opened at contact 652, when the relay V_1 is deenergized. The second group selector II GW is operated in known manner.

The impulses for setting the first and second group selectors I GW and II GW cause circuit changes at the exchange AU_1 of the calling subscriber 35348 and these will now be described. The rotary magnet D_7 of the switch MLW is energized by the first impulse of the first train of impulses as follows: Battery, contact 263, rotary magnet D_7 , contact 264, relay V_{10} , zero contact 265, contact 266, impulse contact 267, earth. Relay V_{10} responds and closes contact 68 so that the circuit for the rotary magnet remains closed even after the wiper has left the contact 265. At the end of this train, which is composed of three impulses, relay V_{10} falls back and the auxiliary relay O is energized as follows: Earth, contact 69 of relay V_{10} , right-hand wiper of MLW, contact 71, relay O , off normal contact 72 of the switch MLW, battery. Relay O connects itself at 73 to a locking circuit, which is only dependent on the off normal contact 72, and also closes the contacts 74 and 75. The first impulse of the second impulse train which operates the second group selector in the exchange A, also energizes magnet D_7 and relay V_{10} over contact 74 of relay O and bank contact 76 of the switch MLW. Relay V_{10} is again energized and closes the contact 68 which is then parallel to contacts 74 and 76 through contact 266, so that the succeeding impulses of the second train can control the magnet D_7 even after the switch wiper has left contact 76.

The second train of impulses is composed of five impulses. Another auxiliary relay N is connected over contact 75 to the eighth contact of the switch MLW. This relay is energized as soon as relay V_{10} is deenergized. It opens its contact 77 and over contact 78 connects itself in a locking circuit, which is only dependent on the off normal contact 72 of the switch MLW. The relay N furthermore short circuits resistance 24 at contact 79, so that the marginal relay C_2 in exchange A can respond. The latter by opening its contact 44 opens the circuit of relay P at the secondary selector ZW and of C_3 in the first group selector I GW. The relay P opens contacts 60 and 61 in the speaking leads which were closed by it when group selector I GW was set. Relay C_3 in the first group selector I GW opens its contact 61, thereby opening the circuit of relay P_1 at the first group selector I GW and C_4 at the second group selector II GW. After relay P_1 has been released, the release magnet M is energized in the following circuit: Earth, contacts 82, 83, release relay M , off normal contact 84 (closed at the first lifting step of the group selector), battery. The numerical switches at exchange A which have been set by impulses transmitted from the sender in the operator's position, are thereby released and are immediately available for another connection.

In addition to the above described circuit changes, the auxiliary relay N brings about the following circuit changes. At contact 84 the test relay P_4 of the switch MLW is connected to the test wiper 85. By opening contact 264 and closing contact 86, the circuit of relay V_{10} is prepared by connecting it to contact 87 of the impulse receiving relay A_1 . By opening contact 88 and closing contact 89, the rotary magnet D_7 is energized as follows: Battery, contact 263, rotary magnet D_7 , contacts 690, 89, 91, earth. The wipers of switch MLW are moved on until they reach a free third group selector III GW, these selectors being connected to the last contacts of the row. Thereupon the following circuit for test relay P_4 is completed: Battery, contact 90, windings II and I of relay P_4 , contact 84, wiper 85, conductor 92, contact 93, relay C_6 , earth. The relays P_4 and C_6 respond. Relay P_4 at contact 91 opens the circuit of the rotary magnet D_7 , at 94 short circuits its high resistance winding I, and at 95 prepares the circuit for the switching relay F . Relay C_6 at contact 96 connects up the relay A_7 . The impulses for setting the third group selector are repeated by the relays A_1 and A_7 to the lifting magnet H_2 . Relay A_7 is intermittently deenergized in the following circuit: Battery, contacts 87, 86, relay V_{10} , conductor 97, contact 96, relay A_7 , earth. It should also be mentioned that relay A_7 at contact 198 en-

ergizes the retardation relay V_{11} , and at contact 99 closes, upon each energization the following circuit for the lifting magnet H_2 : Earth, contacts 100, 99, relay V_{12} , lifting magnet H_2 , shaft contact 101, battery.

- The third group selector III GW is set on a free final selector LW in the same manner as the first group selector I GW was set on a second group selector II GW.
- 10 When a free final selector LW has been found, the relay A_8 is energized over contacts 102, 103, 104 and the speaking lead. At contact 105 it connects up the retardation relay V_{13} , which at contact 106 closes the locking circuit for relay C_7 , which was prepared at 107, and thereby renders this relay independent of the off normal contact 108, which is opened at the first lifting step of the selector.
- 15 The final selector is set in known manner. At the termination of the last train of impulses for rotating the final selector LW onto the required subscriber's line, relay A_1 remains deenergized and consequently relay V_9 deenergizes, which closes the following circuit: Earth, contacts 109, 95, switching relay F, wiper 110, conductor 111, contacts 112, 113, blocking relay S, contacts 114, 115, battery. The blocking relay S closes its contacts 116 and then by opening its contact 114 connects itself to a locking circuit independently of contact 115. The group blocking relay GrS is energized over contact 116 and by opening the contact 115 prevents other S relays being energized. The relay S at contact 117 connects battery over relay G to the incoming lead c_1 of the busy third group selector III GW. Relay F short circuits resistance 13 as follows: Battery, contacts 118, 119, 120, relay C, c -wiper of the second pre-selector II VW, contact 12, winding II of relay T_1 and thence to earth over the c lead and c wiper of I VW. The current over the c -wipers of the second and first pre-selectors is thereby increased and the marginal relay U responds at the second pre-selector. Relay U connects up its winding II over its contact 121, and the contact 122 of the cut off relay T_1 , and by opening the contact 12 and closing the contact 123 switches over the cut off relay T_1 from wiper c to wiper c' , so that relay T_1 is de-energized. The calling relay R_1 is again connected up over contact 3 and the locking circuit for winding 2 of the slow acting relay U is maintained over contact 124 which is parallel to contact 122. The rotary magnet D_1 is again connected up over contacts 16, 10, and the second pre-selector II VW now hunts for the third group selector III GW that has been taken into use by the auxiliary switch MLW. It has already been mentioned that battery has been connected to the incoming lead c' at only one of the free third group selectors III GW,

so that the second pre-selector II VW can only set itself on this group selector. When it has done so, the following circuit is completed: Earth, contact 11, windings I and II of relay T_1 , contact 123, wiper c' of the second pre-selector II VW, c' lead, relay G, contact 117, battery. Relay T_1 effects the same circuit changes as in the case when a free trunk line is taken into use on a subscriber taking off his receiver. Moreover, by closing contact 122, it maintains energized the switching relay U and thereby connects itself to wiper c' for the duration of the conversation. At the third group selector III GW the relay G operates and at contact 124 closes a locking circuit which has been prepared at contact 125. It furthermore opens contacts 113 and 93. Relays C_6 and S and thereby also the group blocking relay GrS are deenergized, causing the removal of the engaged condition at the other group selectors. Relays F and P_4 at the switch MLW are deenergized. The rotary magnet D_1 is energized over contact 91 as follows: Earth, contacts 91, 89, 690, rotary magnet D_1 , contacts 126, 127, battery. The switch MLW is rotated until it reaches its normal position, whereupon the contacts 72 and 127 are opened. Thus the operating circuit of the operating magnet D_1 and the locking circuits of the relays O and N are opened. At this time the off normal contact 15 is also closed so that the trunk line can again be taken into use by a searching second pre-selector.

After the second pre-selector II VW has been set on the third group selector III GW, the bridge relay A_6 is energized, which cuts in the releasing relay V_{11} by closing the contact 128 lying parallel to contact 198. At the end of the conversation, when the circuits of relays A_6 and V_{11} have been opened, the release magnet M_2 is cut in at contacts 129 and 130. The circuit for relays P_5 and C_7 at the final selector LW is at the same time opened at contact 131. The releasing of the final selector LW can take place in any desired manner.

Relay B, Fig. 2, part 2, connected to the trunk line is energized when the connection remains set up over the trunk line and the wanted subscriber answers. Relay B then switches the speaking leads through at contacts 132 and 133. When the connection is established the operator's position, connected up at the exchange A by the service selector DW, is released in the following manner. After all the trains of impulses have been transmitted, relay E is energized over contact 134, and at its contact 135 connects up a relay W, which remains energized for the duration of the conversation over its contact 136 and contact 28 of relay C_1 . Relay W opens a further point in the circuit of the magnet D_2 at contact 31, and at contact 134

opens the circuit of relay T_2 , whereupon relay T_2 falls back and disconnects the wipers of DW.

Figure 3 shows the arrangement of the selectors in a full automatic telephone system, in which large capacity group selectors are used. It is assumed that they each have 20 groups of contacts. If the subscriber T_{n_1} requires connection with the subscriber T_{n_2} , whose number is assumed to be 25632, the first and second pre-selectors are set on the trunk line VL_1 in known manner. The registers for storing up impulses are then operated over a service selector DW. When all the impulses have been stored up, the numerical switches are operated. It will be assumed that the following arrangement is adopted. If a selector is set on a contact group having uneven numbers, the next selector will be set by a train of impulses, comprising a number of impulses, which correspond to the impulses sent out by the calling subscriber. If, however, a numerical switch is set on a contact group bearing an even number, the next numerical switch will be set on a contact group which is reached by 10 plus n impulses, n representing the number of impulses sent out by the subscriber. In the present example the first group selector I GW is set on the second group, then the second group selector II GW on the fifteenth group, the third group selector III GW on the sixth group, and since the latter is again a group with even numbers, the final selector LW is set on the thirteenth group.

The first digits of the subscribers connected to the small exchange AU₁, containing the calling subscriber, are characterized by 35. Hence for a call to this exchange the first group selector I GW is set on the third contact group and the second group selector II GW on the fifth group, whereupon a local third group selector III GW is connected in a similar manner as in the case of Figure 1 by means of a switching device, and the group selectors, which have already been set, are released. When the setting has been completed the subscribers T_{n_1} and T_{n_2} converse over the first and second pre-selectors I VW, II VW, the trunk line VL_3 , the third group selector III GW' and the final selector LW'.

The method of setting up a connection between two subscribers of the same small exchange will now be explained with reference to Figures 4 and 4^a.

When the subscriber T_{n_1} originates a call, the first and second pre-selectors select the trunk line VL_1 , as previously described with reference to Figure 2. Relays A and C associated with the trunk line respond, the latter over contact 155. Relay C at contact 153 prepares its locking circuit, opens contact 156 and by closing contact 157 energizes re-

lay C₁, which is connected to the α -lead at the exchange A. Relay C₂ is not energized by this current and can only be energized when resistance 158 is short circuited in the same manner as in Fig. 2.

The relay A, which was energized by the current over the subscriber's loops, has energized over contact 159 the retardation relay V which, by closing contact 154, has completed the locking circuit for relay C independently of the off normal contact 155. The impulse contact 163 is connected to the α lead of the trunk line over contacts 161 and 162.

The manner of connecting up the register in the exchange A will now be described. The driving magnet D₂ of the service selector DW, Fig. 4^a, part 1, is energized as follows: Earth, contacts 164, 165, 166, rotary magnet D₂, contacts 167, 168, battery. When the service selector DW finds the trunk line, the following circuit is completed: Earth, contacts 169, 170, relay F, wiper 171 of the service selector DW, windings II and I of relay P₁, contact 172, battery. Relays F and P₁ respond, F opens at contact 166 the energizing circuit for the rotary magnet D₂, which is moreover opened by relay P₁ at contact 168, and then closes its contact 173. Relay P₁ marks engaged the found trunk line by short circuiting the high resistance winding I of relay P₁ at contact 174 and closes contact 175. The following circuit is thereby completed: Earth, contacts 168, (Fig. 4, part 1, relay A) 161, 162, a lead of the trunk line VL_1 , conductor 176, contacts 177, 173, wiper 178 of the service selector DW, contacts 175 and 179, retardation relay V₁, contact 180, impulse receiving relay A₁, battery. Relays A₁ and V₁ energize, and relay V₁ closes its contacts 181, 182, 183. The circuit for the driving magnets D₁—D₅ of the five registers Reg. 1—V is prepared at contact 181. Contact 182 connects up the holding magnets HM_{1—5} of the impulse storing registers Reg. 1—V, and the holding magnets HM_{11—15} of the registers Reg. XI—XV which transmit the impulses to the selectors. It is assumed that the registers comprise switching devices having a pawl which engages the cog wheel when a locking magnet is energized, whereupon the switching device can be moved step by step by an electromagnet. The switching devices can, for instance, be returned to their normal position by a spring, when the locking magnets are deenergized.

During the transmission of trains of impulses contact 163 of relay A, Fig. 4, part 1, is opened intermittently, so that the impulse receiving relay A₁, Fig. 4^a, part 1, is intermittently deenergized and the magnet D₁ is energized as follows: Earth, contacts 181, 184, 185, magnet D₁, battery. The retardation relay V₂ is simultaneously energized

- over contacts 181 and 184 and remains operated for the duration of each of the trains of impulses in consequence of its armature being slow to release. It is assumed that the 5 first train of impulses comprises three impulses, so that the register Reg. I is set on the third contact. Relay V_2 is deenergized at the end of this train of impulses. It energizes the switching relay U_1 as follows: 10 Earth, contacts 183, 186, relay U_1 , off normal contact 187 of Reg. I, battery. The switching relay U_1 at contact 188 closes a locking circuit which is independent of contact 186, at contact 185 disconnects the rotary magnet D_1 of Reg. I and, by closing contact 189 connects up the power magnet D_2 of Reg. II. Relay V_2 is again energized by the second 15 train of impulses, and the power magnet D_2 is operated over contacts 181, 184, 189, 190. 20 When this train of impulses are completed, the switching relay U_2 is energized over contacts 183 and 191 and is locked over contact 193, it disconnects the magnet D_2 by opening contact 190 and at contact 194 connects up the power magnet D_3 of the register Reg. III. All the five registers are set in 25 this manner by impulses transmitted by the calling subscriber.
- When the fifth register has been set, a relay F is energized as follows: Earth, contact 195, relay F , off normal contact 196 of register Reg. V, battery. Relay F at contact 180 disconnects the impulse receiving relay A_1 , and at contact 197 connects up the impulse contact 198. Moreover, the impulse relay J is energized as follows: Earth, contact 199, impulse relay J , contacts 200, 201, 202, 203, 204, battery. The relay F furthermore by closing contact 205 energizes a steering 30 relay V_{11} and the rotary magnet D_{11} of the register Reg. XI as follows: Earth, contact 205, relay V_{11} , rotary magnet D_{11} , contacts 206, 207, battery. Since the register Reg. I is set on the third contact as mentioned above the wiper 208 is set on a contact to which relay E is not connected. The contacts of the register Reg. I and those of register Reg. XI are interconnected, so that the contact on which register Reg. I was set is accordingly found in three steps and the circuit of the impulse relay J is three times opened at contact 200 of rotary magnet D_{11} . Thus, three impulses are transmitted by contact 198. When the register Reg. XI finds the contact on which register Reg. I was set, the following circuit is closed: Earth, contact 209, of relay V_{11} , wiper 211, contact 212, conductor 213, contact 214, wiper 215, relay P_{11} , battery. Relay P_{11} at contact 207 opens the circuit of the rotary magnet D_{11} and of the steering relay V_{11} .
- The further operation of the register will now be explained and then the circuit changes in the trunk line as well as in the exchanges A and AU₁ will be explained.

When relay V_{11} is deenergized it connects the rotary magnet D_{12} and the relay V_{12} in the following circuit: Earth contact 216, off normal contact 217 of register Reg. XII, relay V_{12} , rotary magnet D_{12} , contacts 218, 219, 70 battery. As Reg. I has been set on a contact with an uneven number, the second train of impulses comprises only five impulses. When the register Reg. XII reaches the fifth contact, relay P_{12} is energized as follows: 75 Earth, contact 220, wiper 221, contact 222, conductor 223, contact 224, wiper 225, relay P_{12} , battery. Relay P_{12} at contact 219 opens the circuit for magnet D_{12} . Relay V_{12} , which is deenergized as a result of this, connects 80 up the register Reg. XIII. The five impulses are, accordingly, transmitted to the selectors by the opening of contact 201 in the circuit of relay J. Impulses are thus sent out by all five registers Reg. XI—XV. 85

If register Reg. I is set by six impulses, relay E is energized over contact 222 and closes its contact 226. Now when the register Reg. XII is operated relay U_r is energized over wiper 227 at each of the first ten 90 contacts. Relay U_r closes its contact 228, thereby maintaining the circuit for the rotary magnet D_{12} even when wiper 225 is set on a contact 224, which is connected to the contact of the register Reg. II on which 95 wiper 221 has been set. The lines coming from the register Reg. II are connected to two of the bank contacts belonging to the wiper 225 of the register Reg. XII, namely 100 at the first and last 10 contacts. Hence the line connected to contact 224 is also connected to contact 229. Register Reg. XII accordingly takes fifteen steps and the numerical switch is set on the fifteenth contact group. 105

When all the five registers Reg. XI—XV have been set, the following circuit for relay F_1 is closed: Earth, contact 230, off normal contact 231, of register XV, relay F_1 , battery. The operations effected by this relay 110 will be explained hereafter.

It will be understood that while the switch DW is connecting the register to the trunk line VL₁, that has started it up, the secondary selector ZW is simultaneously set on a first group selector in the manner already explained with reference to Figure 2.

Returning now to the point at which, when all the impulses transmitted by the subscriber have been registered, the relay F_1 , Fig. 4_a, part 1, is energized as already mentioned, this relay, in addition to the above described switching operations, closes the following circuit: Battery, contacts 232, 233, wiper 234 of the service selector DW, 120 relay G, contacts 235, 236, earth. Relay G closes at contact 237 the following circuit for relay B at the exchange of the calling subscriber: Battery, resistance 238, contact 237, b-lead of the trunk line, relay B, earth. 125 130

Relay B opens its contact 239, thereby preventing the calling subscriber being prematurely connected to a numerical switch at his own exchange. Moreover contact 162 is opened and contact 240 is closed, so that the impulse relay A_1 is connected up instead of impulse contact 163. Relay A_1 is energized over the impulse contact 198 of the registers and, by closing contact 241 energizes the retardation relay V. Therefore, the switch MLW is set and a third group selector is selected in the manner already described with reference to Fig. 2.

When all the numerical switches have been set, relays A_1 and B are deenergized, because contact 232 of relay F_1 at the registers is opened upon the hereinbefore pointed out energization of relay F_1 . Relay B by closing its contact 244, energizes the relay S in the manner described with reference to Fig. 2 over contact 245 and wiper 246 of the switch MLW. When relay S closes its contact 247, it renders only one line ready for testing. At the same time the resistance 248 is short circuited by contacts 243, 239 and 249, so that the second pre-selector is set on the third group selector, which has been taken into use by the switch MLW. Thereupon relay G is operated as described with reference to Fig. 2 and by opening contact 250, deenergizes the test relay P_4 of the switch MLW. The switch MLW advances to its normal position, whereupon the trunk line VL₁ is ready for another connection.

As soon as the relay N at the switch MLW was energized it closed contact 251 and thereby in the manner described for Figure 2, it caused the release of the numerical switch that was first operated by the registers. If relay C is deenergized as a result of the interruption of the current over the c wiper of the second pre-selector, then relay C₁ is also deenergized in consequence of the opening of the contact 157 and all the circuits in the exchange A are opened.

After relay F_1 has been energized by the setting of the register Reg. XV the circuit for relay F is opened and relay W is connected up over contacts 252 and 253. Relay W is locked over its contact 254 and contact 255 of relay C₁, and by opening contacts 165, 170, 235, frees the trunk from the service selector. The locking circuit of relay W is opened when relay C₁ is deenergized.

In the example shown in Fig. 5 the second pre-selector is at once set on a numerical switch at the local exchange, when this switch has been operated by the switch MLW. In this example the resistance 300 is short circuited by relay F₂, which operates as soon as the switch MLW has been set on a free third group selector. Moreover, the relay S, energized in the circuit of relay F_2 , in the known manner, renders selectable only that third group selector II GW which was

found. The current over the test wiper of the second pre-selector II VW is increased owing to the short circuiting of the resistance 300, when contacts are closed at 301 of the auxiliary relay N, 302 of relay F₂ and 303 of the bridge relay A. The switch MLW is maintained in the set position by contact 304 of relay B after the calling line has been switched over. The relay B also maintains the current over lead c of the trunk line by closing its contact 305 which is parallel to contact 306 of relay C.

After the test relay of the second pre-selector has been switched over to the special wiper, as described above, the relay C is deenergized and opens its contact 307. The trunk line, however, remains engaged because contact 308 (off normal contact of switch MLW) is open while the switch MLW is in the operated position.

When all the numerical switches have been set the relays B and P₄ are released, whereby the rotary magnet D₇ of the switch MLW is energized in the circuit: Earth, contacts 309, 310, 311, magnet D₇, contacts 312, 313, battery. When the switch MLW has reached its normal position, this circuit is opened at contact 313 and the locking circuit for O and N is opened at contact 314. At the same time contact 308 is closed and the trunk line VL₁ can now be taken into use by another second pre-selector.

What I claim and desire to protect by Letters Patent is:

1. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a sender in the second exchange, means controlled by said sender for further extending said connection by way of switches in the second exchange, means effective when enough switches in the second exchange have been set to determine that the calling line is to be reached by way of the first exchange for releasing the operated switches in the second exchange, means for subsequently extending a connection from the first exchange end of said trunk line to the called line by way of switches in the first exchange, and means effective only after the switches have been set for releasing said trunk line.

2. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a sender in the second exchange, means controlled by said sender for

- further extending said connection by way of switches in the second exchange, means effective when enough switches in the second exchange have been set to determine that the calling line is to be reached by way of the first exchange for releasing the operated switches in the second exchange, means for subsequently extending a connection from the first exchange end of said trunk line to the called line by way of switches in the first exchange, and means controlled by said sender and effective only after the switches have all been set for releasing said trunk line.
3. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a sender in the second exchange, means controlled by said sender for further extending said connection by way of switches in the second exchange, means effective when enough switches in the second exchange have been set to determine that the calling line is to be reached by way of the first exchange for releasing the operated switches in the second exchange, means for subsequently extending a connection from the first exchange end of said trunk line to the called line by way of switches in the first exchange, and means controlled by said sender and effective only after the switches have all been set for connecting said calling line with the called line through the locally operated switches and over a path independent of said trunk line and for releasing said trunk line.
4. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a register sender in the second exchange, means for repeating impulses representing the called number over said trunk line to said register sender, means controlled by said register sender for registering the called number transmitted to it over said trunk line, means controlled by said register sender when the complete number is registered for disconnecting said repeating means and for connecting up an impulse receiving relay, means in said register sender for transmitting impulses to said automatic switches in the second exchange to extend the connection forward and for simultaneously sending impulses back over said trunk line to said repeating relay, means controlled by said repeating relay for registering one or more of the digits of the number and for operating switches in the first exchange in accordance with the remaining digits of the number to connect with the called line in case the digit or digits registered are characteristic of the called exchange, means controlled by said register sender for releasing the operated switches in the second exchange when said characteristic digit or digits are registered, means exclusive of said repeating relay and controlled by said register sender for enabling the calling line to be connected to the called line through the operated switches in the first exchange, and means controlled by said last named means for releasing said trunk line after all the switches have been set.
5. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a register sender in the second exchange, means for repeating impulses representing the called number over said trunk line to said register sender, means controlled by said register sender for registering the called number transmitted to it over said trunk line, means controlled by said register sender when the complete number is registered for disconnecting said repeating means and for connecting up an impulse receiving relay, means in said register sender for transmitting impulses to said automatic switches in the second exchange to extend the connection forward and for simultaneously sending impulses back over said trunk line to said repeating relay, means controlled by said repeating relay for registering one or more of the digits of the number and for operating switches in the first exchange in accordance with the remaining digits of the number to connect with the called line in case the digit or digits registered are characteristic of the called exchange, means controlled by said register sender for releasing the operated switches in the second exchange when said characteristic digit or digits are registered, means exclusive of said repeating relay and controlled by said register sender over a talking conductor of said trunk line for enabling the calling line to be connected to the called line through the operated switches in the first exchange, and means controlled by said last named means for releasing said trunk line after all the switches have been set.
6. In a telephone system, a first exchange, a second exchange, automatic switches in both exchanges, a trunk line extending from the first exchange to the second exchange, means in the first exchange for extending a connection from a calling line in the first

exchange to the second exchange by way of said trunk line, a sender in the second exchange, means controlled by said sender for further extending said connection by way of switches in the second exchange, means effective when enough switches in the second exchange have been set to determine that the calling line is to be reached by way of the first exchange for releasing the operated switches in the second exchange, means for subsequently extending a connection from the first exchange end of said trunk line to the called line by way of switches in the first exchange, and means effective only after the switches have been set for releasing said trunk line, said means for releasing the switches in the main exchange being controlled over a conductor of said trunk line separate from the talking conductors.

7. In a telephone system, a first exchange, a second exchange, automatic switches in both exchanges, a trunk line extending from the first exchange to the second exchange, means in the first exchange for extending a connection from a calling line in the first exchange to the second exchange by way of said trunk line, a sender in the second exchange, means controlled by said sender for further extending said connection by way of switches in the second exchange, means effective when enough switches in the second exchange have been set to determine that the calling line is to be reached by way of the first exchange for releasing the operated switches in the second exchange, means for subsequently extending a connection from the first exchange end of said trunk line to the called line by way of switches in the first exchange, means effective only after the switches have been set for releasing said trunk line, a relay in the second exchange, and means for operating said means for releasing the switches in the second exchange by operating said relay by increasing the current through it.

8. In a telephone system, a first exchange, a second exchange, a trunk line connecting said exchanges, means for extending a connection from a calling line in the first exchange to the second exchange by way of said trunk line, an impulse sender in the second exchange, means including said

sender for transmitting impulses representing digits in a telephone number to said trunk line, automatic switches in the second exchange responsive to said impulses to extend the connection on toward the desired line, a register in the first exchange responsive to such digits to connect up over a tentative path a local selector in case such digits determine that the called line is to be reached by way of the first exchange, means controlled by the remaining impulses for operating said selector over said tentative path, means controlled by said sender for connecting the calling line to said local selector over a new path, and means for preventing said calling line from being connected with another local selector and for preventing another line from being connected with the first named local selector.

9. In a telephone system, a first exchange, a second exchange, a trunk line connecting said exchanges, means for extending a connection from a calling line in the first exchange to the second exchange by way of said trunk line, an impulse sender in the second exchange, means including said sender for transmitting impulses representing digits in a telephone number to said trunk line, automatic switches in the second exchange responsive to said impulses to extend the connection on toward the desired line, a register in the first exchange responsive to such digits to connect up over a tentative path a local selector in case such digits determine that the called line is to be reached by way of the first exchange, means controlled by the remaining impulses for operating said selector over said tentative path, means controlled by said sender for connecting the calling line to said local selector over a new path, and means controlled by said local selector for preventing said calling line from being connected with another local selector and for preventing another line from being connected with the first named local selector.

In witness whereof, I hereunto subscribe my name this 29th day of May A. D., 1923.

WALTER PINELL.
